Des. 235,917
Patented July 15, 1975

235,917

FUEL DISPENSING CONSOLE

Richard C. Hickey, Plano, and Edward H. McCauley,
Dallas, Tex., assignors to Docutel Corporation, Irving
Tex.

Filed Jun. 26, 1973, Ser. No. 373,796

Term of patent 14 years

Int. Cl. D20—01

U.S. CL. D52—2 A

FIG. 1

FIG. 2

FIG. 3

FIG. 4

FIG. 1 is a front perspective view of a fuel dispensing terminal console showing our design;

FIG. 2 is a front elevation thereof;

FIG. 3 is a right side elevation thereof; and

FIG. 4 is a left side elevation thereof.

The back and top are plain and unornamental.

We claim:

The ornamental design for a fuel dispensing console, as shown and described.
